(57) **CLAIM**

The ornamental design for a refill pack for a simulated cigarette device, as shown and described.

DESCRIPTION

FIG. 1 is a first perspective view of a refill pack for a simulated cigarette device showing our new design.

FIG. 2 is a second perspective view of the refill pack for a simulated cigarette device in an open position.

FIG. 3 is a front view of the refill pack for a simulated cigarette device.

FIG. 4 is a back view of the refill pack for a simulated cigarette device.

FIG. 5 is a side view of the refill pack for a simulated cigarette device; and,

FIG. 6 is top view of the refill pack for a simulated cigarette device.

The broken lines shown in the drawings are for illustrative purposes only and form no part of the claimed invention.
